US0D1068254S

(12) **United States Design Patent** (10) Patent No.: **US D1,068,254 S**
(45) Date of Patent: ** *Apr. 1, 2025

(54) **BACKPACK**

(71) Applicant: **Upper Echelon Products LLC**, Austin, TX (US)

(72) Inventors: **Michael Joseph Zucco**, Austin, TX (US); **Grigory Alexandrovich Markov**, Nizhny Novgorod (RU)

(*) Notice: This patent is subject to a terminal disclaimer.

(**) Term: **15 Years**

(21) Appl. No.: **29/921,618**

(22) Filed: **Dec. 18, 2023**

Related U.S. Application Data

(63) Continuation of application No. 29/865,331, filed on Jul. 20, 2022, which is a continuation of application No. 29/791,636, filed on Jan. 25, 2022, now Pat. No. Des. 1,013,367.
